UNITED STATES PATENT OFFICE

REUBEN C. BAKER, OF COALINGA, CALIFORNIA, ASSIGNOR TO BAKER OIL TOOLS, INC.,
OF HUNTINGTON PARK, CALIFORNIA, A CORPORATION OF CALIFORNIA

WELL PUMPING RIG

Application filed January 21, 1930. Serial No. 422,354.

This invention relates to deep well pumping rigs.

In counterweighting pitmans to compensate for the well load, the counterweight is necessarily so heavy that it is extremely difficult to handle to enable repairs, adjustments, etc. to be made. It is the principal object of the present invention to provide a well pumping rig wherein the counterweighted 5 pitman may be easily engaged or disengaged from the crank pin without the use of auxiliary apparatus.

In carrying this invention into practice I provide a walking beam so connected to the 15 samson post that it may swing horizontally as well as vertically. The pitman is fitted with a jacking carriage so that its weight may be relieved from the crank pin and the beam and pitman easily moved relative 20 thereto.

One form which the invention may assume is exemplified in the following description and illustrated by way of example in the accompanying drawings, in which:

25 Fig. 1 is a side elevation of a pumping rig embodying my invention.

Fig. 2 is a plan view of same showing the pitman disconnected from the crank pin.

Fig. 3 is an end view of the rig.

30 Fig. 4 is a fragmentary view in side elevation of the pitman counterweight with the jack disengaged from the track.

Fig. 5 is an enlarged fragmentary view in section showing the mounting of the jack in 35 the counterweight.

Referring more particularly to the accompanying drawings, 10 indicates a portion of a deep well pumping rig. This rig includes the usual oscillating walking beam 11 which 40 is supported at its center upon a samson post 12. The connection between the walking beam 11 and the samson post 12 is a universal one so that the walking beam may oscillate in a vertical or a horizontal plane. 45 This connection per se forms the subject matter of my copending application entitled "Walking beam swivel," filed January 21, 1930, Ser. No. 422,353.

One end of the walking beam is connected 50 to the sucker rod of the well pump in the

usual manner as illustrated. The other end of the walking beam is connected by means of a pitman 14 to a crank pin 15 arranged at an eccentric point on the band wheel 15a.

The pitman 16 is fitted with a stirrup 17 55 by means of which it is suspended from the walking beam.

The other end of the walking beam is fitted with a large counterweight 18 equipped with a crank pin bearing 19 which connects with the crank pin 15. The former is operative so that it may be quickly expanded to release the crank pin when desired. The novel arrangement and construction of the counterweight 18 and its bearing is fully described and claimed in my copending applications entitled "Counterweight pitman," filed Jan. 21, 1930, Ser. No. 422,355, and "Pitman bearing," filed Jan. 21, 1930, Ser. No. 422,352.

Reference being had to Fig. 5 it will be seen that a screw shaft 20 is threaded upwardly into the lower end of the counterweight through a feed nut 21 rigidly secured to the counterweight 18. The lower end of the screw shaft 20 is fitted with a yoke 22 carrying a wheel or roller 23. This roller is adapted to engage a track 24 on the derrick floor or on the ground or base surrounding the rig. This track may be arcuate and concentric to the point of connection between the pitman and the samson post. However, the track may be of sufficient width so that it need not be arcuate. In fact, under some circumstances the track may be eliminated and the roller bear directly on the base. 75 80 85

Under usual conditions the counterweight will weigh approximately four tons.

In operation, the rig is assembled as illustrated. When it is desired to disconnect the pitman, the screw shaft 20 is rotated until the roller at the end thereof engages the track or base. Continued rotation of the shaft will jack the counterweight up and relieve the weight from the crank pin 15. The pin bearing may then be expanded to release the 90 95 crank pin.

When the walking beam has been disconnected from the pump rod, the entire walking beam and pitman may be swung horizontally to disengage the pitman from the crank pin. 100

It is obvious that during this time the weight will be sustained by the roller 23.

In this manner the counterweighted pitman may be handled with ease. Hitherto, it was difficult to sufficiently counterweight pitmans because of the extreme difficulty in handling the same.

From the foregoing it is obvious that I have provided a rig enabling the pitman to be fully counterweighted for the well load and still be easily handled.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. An apparatus of the character described including a walking beam, a revoluble crank, a pitman connecting the walking beam and crank, and means connected with the pitman and capable of sustaining the weight of the same relieving the weight thereof from the crank while the pitman is still connected with the crank.

2. A pumping rig including a horizontally disposed revoluble crank pin, a horizontally disposed walking beam mounted thereabove and extending at right angles to said crank, a vertically disposed counterweighted pitman connecting the crank pin to the walking beam, means for relieving the crank pin of the weight of the pitman while the pitman is still connected therewith, and a universal mounting for said walking beam enabling said pitman to be moved axially along the crank without disconnecting the pitman from the walking beam when the crank is relieved of the weight of the pitman.

3. A pumping rig including a revoluble crank pin, a walking beam arranged thereabove, a counterweighted pitman connecting the crank pin to the walking beam, and jacking means connected with the pitman and disposed beneath the same for elevating the pitman and relieving the crank pin of the weight thereof.

4. A pumping rig including a revoluble crank pin, a walking beam mounted thereabove for universal movement, a counterweighted pitman connecting the crank pin to the walking beam, jacking means connected with the pitman and disposed beneath the same for relieving the crank pin of the weight of the pitman, said jacking means having a roller thereon enabling withdrawing said pitman from engagement with the crank pin while the jacking means is supporting the pitman.

5. A pumping rig including a revoluble crank pin, a universally movable walking beam mounted thereabove, a counterweighted

pitman connecting the crank pin to the walking beam, jacking means connected to the pitman whereby said pitman may be supported, said jacking means being supported on a roller to permit movement of the pitman laterally while so supported.

6. A pumping rig including a revoluble crank pin, a universally movable walking beam mounted thereabove, a counterweighted pitman connecting the crank pin to the walking beam, and a mobile jack operatively connected with the pitman whereby the pitman may be supported and moved laterally while so supported.

7. A pumping rig including a revoluble crank pin, a universally movable walking beam mounted thereabove, a counterweighted pitman connecting the crank pin to the walking beam, a mobile jack operatively connected with the pitman for supporting the weight of the pitman, and means for guiding the movement of said jack.
